UNITED STATES PATENT OFFICE

WALTER SIEGERIST, OF BAYSIDE, NEW YORK, ASSIGNOR TO INTERNATIONAL COMBUSTION ENGINEERING CORPORATION, OF NEW YORK, N. Y., A CORPORATION OF DELAWARE

BOILER INSTALLATION

Application filed March 5, 1929. Serial No. 344,259.

The invention relates to boiler installations and is particularly directed to improvements in the arrangement of steam purifiers or separators in boiler installations having 5 water walls in the combustion chambers thereof.

One of the primary objects of my invention is to provide a boiler installation including a steam purifier in which separated 10 water from the purifier is returned to the boiler in an effective manner.

More specifically it is an object of my invention to provide a boiler installation including water walls in the combustion chamber and a steam purifier in which separated water from the purifier is returned to the 15 boiler through a water wall or walls.

Another object is to provide an installation of the character described in which separated 20 water from the purifier is delivered into the boiler circuit at such point or points as will be advantageous from the standpoint of head conditions.

A further object is to provide a boiler installation including a multi-stage purifier in 25 which separated water from the various stages is returned to the boiler at various low points therein.

How the foregoing, together with such 30 other objects and advantages as may herein-after appear, or are incident to my invention, are realized, is illustrated in preferred form in the accompanying drawing, wherein—

Fig. 1 is a more or less diagrammatic 35 sectional elevation through a boiler installation constructed in accordance with my invention, and

Fig. 2 is a similar view illustrating a 40 modification of the invention.

In the drawing the boiler A, which is illustrated as being of the Stirling type, is provided with a combustion chamber B located 45 in front of and largely beneath the boiler.

The combustion chamber is provided with 50 water walls defining combustion space, and in the drawing a front water wall C and a rear water wall D are shown.

The front water wall C is composed of 55 two sets of upright tubes 3 and 4, each comprised of a plurality of closely spaced boiler

tubes. The tubes of the lower set 3 are connected at their lower ends into a header 5 and at their upper ends into a header 6. The tubes of the upper set 4 are connected at their lower ends into the header 6 and at 55 their upper ends into the header 7. Thus, it will be seen that the two sets in effect constitute a single front water wall. Water is delivered to this water wall by means of down-comers 8 leading from the lower drum 9 of the 60 boiler A to the lower header 5 of the wall, and the tubes of the wall deliver into the upper drum 10 of the boiler through the medium of a plurality of roof tubes 11.

The rear water wall D is composed of a 65 plurality of upright closely spaced boiler tubes 12 connected at their lower ends into the lower header 13 and at their upper ends into the drum 9. Water is delivered to this wall by means of down-comers 14 leading 70 from the drum 9 to the header 13, and the tubes of the wall deliver into the drum 9.

A steam purifier or separator E is associated with the boiler and may be of any 75 suitable type. The purifier is preferably located slightly above and adjacent to the upper steam and water drum 15 of the boiler A. A connection 16 delivers steam from the boiler to the purifier and an outlet 17 is 80 provided for steam take-off.

The purifier or separator operates to remove moisture from the steam which collects in the lower portion thereof.

In order to avoid wasting the collected 85 water, I propose to return the water into the boiler circulation, and I contemplate the accomplishment of this in a novel manner whereby substantial quantities of water may be returned very effectively.

Referring to Fig. 1, it will be seen that 90 a downcomer 18 leads separated water from the lower portion of the purifier E to the lower header 5 of the front water wall C, and that a downcomer 19 leads separated water 95 from the purifier to the lower header 13 of the rear water wall D. I may also lead water from the purifier to the lower drum 9 of the boiler, as by means of a down-comer 20. I prefer to provide each of the 100

downcomers 18, 19 and 20 with check valves as diagrammatically illustrated at 21.

The particular type of purifier illustrated is a horizontally disposed multi-stage one, and in the form illustrated in Fig. 1 each stage is connected to a different head point of the installation. For example, the first stage 22 is connected to lower boiler drum 9, the second stage 23 to the lower rear wall header 13, and the third stage 24 to the lower front wall header 5.

In the form illustrated in Fig. 2 all of the stages are connected to the lower front wall header 5 by means of pipes 18a, 19a and 20a leading to a common pipe 25 which, in turn, leads to the header 5. Check valves in the pipes 18a, 19a and 20a are indicated at 21a.

By leading water from the purifier E to the boiler A through the water walls to which the connection is made at a low point, there is provided a very effective arrangement for the reason that inasmuch as the water walls are subject to radiant heat, and consequently do considerable work, the mixture in the tubes of the wall is of much lower density than the substantially solid water in the downcomers leading from the purifier.

Under normal operating conditions the water in the downcomers 18, 19 and 20 will be of greater density so that normally there will always be a down circulation. With respect to the downcomers 8 and to the downcomers 18 this is also true and the water contained therein is of much more density than the mixture in the front wall in consequence of which there will normally be a downflow in both sets of tubes.

Stated in another way the downcomer 18, for example, may be considered as one leg of a U-tube, and the tubes of the water wall C may be considered as the other leg thereof, and owing to the fact that there is rapid evaporation in the tubes of the wall, they will contain a mixture of water and steam which is materially less dense than the water containing no steam, which is in the downcomer 18 located outside of the hot zone of the installation. Therefore, it may be said that I utilize the additional head obtained due to the lower density of the mixture of steam and water in the water walls to aid in discharging water from the purifier to the boiler. The same applies, only in a somewhat less degree, to the connection 19 leading to the rear water wall D.

I claim:—

1. The combination with a water tube boiler of a combustion chamber therefor having a wall defined by upright boiler tubes connected into the boiler circulation, a steam separator, a connection for leading steam from the boiler to the separator, and means for discharging moisture from the separator into the boiler comprising downcomers out-

side the boiler circulation for leading the moisture to the upright boiler tubes.

2. The combination with a water tube boiler, of a combustion chamber therefor, rows of boiler tubes defining walls of the combustion chamber, lower headers into which the tubes of said rows are connected, downcomer means for leading water to said headers from the boiler, said tubes being connected to deliver to the boiler, a steam separator, a connection for leading steam from the boiler to the separator, and downcomer means outside the boiler circulation for leading water from the separator to the boiler through said water walls.

3. The combination with a water tube boiler, of a combustion chamber therefor, rows of boiler tubes in the chamber connected into the boiler circulation and defining combustion space, a multi-stage steam separator connected to the boiler to receive steam therefrom, and downcomer means connecting each stage of the separator to a different low point in the boiler circuit.

4. The combination with a water tube boiler, of a combustion chamber therefor the major portion of which is located below the level of the boiler, rows of upright tubes in the chamber arranged to define combustion space and extending upwardly from the lower portion of the chamber, headers into which the lower ends of the tubes of said rows are connected, said tubes being connected at their upper ends to deliver into the boiler, downcomer means leading from the boiler to said headers, a steam separator connected to the boiler to receive steam therefrom, and downcomer means outside the boiler circulation leading from the steam separator to the lower headers whereby water is supplied to the upright tubes from the separator.

In testimony whereof I have hereunto signed my name.

WALTER SIEGERIST.
